CLAIM

The ornamental design for a tool holder, as shown and
described.

DESCRIPTION

FIG. 1 is a perspective view of a tool holder showing
our new design;

FIG. 2 is a front elevational view, the rear being flat and
unornamented;

FIG. 3 is a top plan view thereof;

FIG. 4 is a left side elevational view thereof;

FIG. 5 is a right side elevational view thereof; and

FIG. 6 is a bottom plan view thereof.
